FUEL SUPPLY SYSTEM

George F. Noltein, Springfield, Ohio, assignor to
Superior Engine Company, Inc., Springfield,
Ohio, a corporation of Delaware

Application January 27, 1930, Serial No. 423,704

7 Claims. (Cl. 123—140)

My invention relates to a fuel supply system for internal combustion engines.

It is the object of my invention to provide a governor controlled fuel supply system in which the operation of the governor can be adjusted at any predetermined setting, within which range the fuel control system will operate.

It is a further object to provide a fuel by-pass system in order that excessive fuel may be bypassed back to the source of supply, and this adjustment for by-passing may be varied according to the conditions of operation of the apparatus, thereby attaining a fuel pressure as desired.

It is a further object to provide this control system to facilitate starting of the engine, the regulation of the speed of the engine after starting, the regulation of the fuel supply, all in combination with an injector, through which solid fuel is injected under a predetermined fuel pressure being admitted at intervals according to the mechanical adjustment of the adjusting mechanism of this invention by mechanical operation of the fuel injector.

Referring to the drawings:

Figure 1 is a diagrammatic view of the fuel system;

Figure 2 is a section on the line 2—2 of Figure 1 showing the details of the fuel by-pass control;

Figure 3 is an enlarged detail view partially in section showing the fuel by-pass arrangements and the relationship of the control levers;

Figure 4 is a detail view of the fuel control system showing the relative position of the control shafts with certain of the parts removed for the purpose of clearness, such as the quadrants, etc.;

Figure 5 is a skeleton view showing the relative positioning of the injector, the control mechanism for determining the amount of fuel, the cam shaft, cam, push rod and rocker arm construction for operating the fuel injector;

Figure 6 is a detail view showing the fuel relief valve adjustment, rocker and cam;

Figure 7 is a section through the injector in its closed position;

Figure 8 is a section on the line 11—11 of Figure 1 showing in detail the governor mechanism and the governor control.

Referring to the foregoing views, 1 represents a pipe line from a tank that supplies the fuel through a pump indicated diagrammatically at 2 and suitably driven from any source of power, such as the engine itself, or otherwise. The fuel is ejected from the pump through the line 3 and thence passes through the pipe 4 to the fuel

injector shown in Figure 5. Fuel is also delivered through the pipe 5 to the by-pass valve 6 which is adapted to be opened by the fuel pressure therein in order to pass fuel oil through the pipe 7 back to the tank from which the pipe 5 draws the fuel in the event that the fuel has exceeded a predetermined pressure, as herein-after determined.

Fuel by-pass system

When the fuel passes through the pipe 5, it enters the chamber 8 beneath the shoulder 9 and tends to lift the needle valve stem 10 which closes the port 11 that shuts off the passage of fuel between the pipe 5 and the pipe 7.

The lifting of the needle valve 10 is resisted by the spring 12 which is mounted on the cap 13 at one end and rests against the cap 14 at the other end.

The cap 14 is engaged by a stud 15 carried on the rocker arm 16 which, in turn, is mounted on the shaft 17. The movement in one direction, that is, upwardly, of the rocker arm 16 is limited by the set screw 18 which is locked in position by the nut 19. This set screw is carried by the cover 20 which forms a part of the housing for this mechanism.

The other end of the rocker arm 16 opposite to that carrying the stud 15 has a stud 21 which engages with the fuel relief valve eccentric 22, 30 which is keyed to the shaft 23 by the key 24 and clamped thereon by the bolt 25.

The compression of the spring 12 is thus controlled and, therefore, the pressure at which the valve stem 10 is lifted is controlled. The pressure of the fuel is thereby regulated. The shaft 23, which carries the fuel relief valve eccentric 22, has connected thereto the governor control handle 26 which serves to rotate and position it.

Governor adjustment mechanism

The governor adjustment lever 26 is positioned by the detent 27 engaging the toothed quadrant 28. The detent 27 is disengaged from the quadrant 28 by the depression of the sleeve 26a 45 against the spring 29 which serves to carry the reciprocating plunger 30 downwardly and with it the detent 27.

On the shaft 23 is mounted the governor adjustment arm 31 which, in turn, carries the 50 transversely extending governor adjustment lever 32 which has the cam face 33 riding upon the governor spring cup 34 which, in turn, rests upon the governor spring 35. The upper end of this spring is encased within the sleeve 36 of the sup- 55

porting cover 37 of the casing. The lower end of this spring 35 rests within the governor cup 38 which in turn rests upon the ball bearings 39.

The under side of the ball bearings 39 carries 5 the collar 40 and sleeve 41. This collar and sleeve are guided upon the shaft 42 and are adapted to reciprocate thereon as they travel with the cup 38 during the course of expansion or compression of the spring 35 of the governor. 10 The under side of this collar 40 carries depending ears 43 and rollers 44 that are engaged by the governor arms 45 which are connected to the governor weights 46 that are pivoted at 47 upon the ears 48 of the governor yoke. This yoke is 15 keyed by the key 49 to the shaft 42 and rests upon the tapered bearings 50 within the governor housing 51. The outward movement of the weights 46, due to centrifugal force applied thereto by the rotation of the governor, will serve 20 to compress the spring 35. The state of compression of the spring initially is determined by the setting of the governor adjustment lever 26. The governor housing 51 may be partially filled with oil through the pipe 52, if desired.

25 Thus, the sensitiveness or responsiveness of the governor is determined by the predetermined compression of the spring 35. This is likewise synchronous through the adjustment of the common handle 26 with the compression of the 30 spring 12 of the by-pass valve so that the maximum pressure of the oil comprising the fuel delivered to the engine will depend upon the adjustment of the governor. The cup 38 is provided with studs 38a engaging the arms of the 35 yoke 38b which is mounted on the shaft 67.

The governor is driven in the usual manner by the bevel pinion 42a, bevel gear 42b and cam shaft 42c.

40 *Control of the fuel amount delivered*

In order to control the amount of fuel delivered, which ranges from starting of the engine to normal operation, I have provided the fuel control lever 53 which is provided with a telescoping sleeve 54 that moves the plunger 55 against the spring 56 to operate a detent, such as the detent 27 in conjunction with the quadrant 57. This lever is mounted upon the shaft 58. The shaft 58 carries the governor rod control 50 yoke 59 which is provided with the cam nose 60 engaging the collar 61 which is pinned to the governor rod 62. This rod is slidably mounted within the shaft 63 and is retained therein by the nut 64. Between the collar 61 and the shaft 55 63 is the helical spring 65 surrounding the shaft 62. The shaft 63 is carried in the yoke 66 pivoted upon the shaft 67 that is suitably carried upon the frame work of the engine. Connected to the yoke 66 is an arm 68 that is in turn connected to a piston rod 69 and piston 70 working within the cylinder which is pivotally mounted at 72 by the bracket 73 to any suitable part of the engine. This piston 70 fits loosely within the cylinder 71 and acts as an oil brake or dash 60 pot.

The upper end of the rod 62 is pivotally connected at 74 to the lever 75 that is fixed upon the shaft 76 by the clamping jaws 77 and bolts 78. On this shaft is mounted an arm 79 which carries pivotally at 80 a wedge 81 which is interposed between the fuel injector, rocker arm 82 and the cam shaft rocker arm 83. A set screw 84 carried by the latter arm adjusts this connection.

75 The cam shaft rocker arm is actuated by the

push rod 85, cam 86 and cam shaft 87 driven from the engine. The adjustment of the position of the shaft 58 by the lever 53 will determine the position of the wedge 81. When the wedge is withdrawn to its rearwardmost position, there is substantially no opening of the injector and no fuel is admitted. As the wedge is inserted, more and more fuel is injected. When the shaft and its governor rod control yoke 59 are in starting position, the parts are as indicated in dotted lines. The yoke 59 has the position marked A. The running position is where the yoke is in position B. The stop position in which the wedge 81 is withdrawn so no fuel is being admitted is where the yoke is in position C 15 shown in full lines.

Thus, the lever 53 controls the starting, running and stopping positions and determines in connection with a certain fuel pressure the quantity of fuel to be delivered.

5

20

25 *Injector*

The injector, as shown in Figure 7, is actuated by the injector rocker 82 which is pivoted at 88 on the body 89 of the injector. The inner end of this rocker 82 is provided with a cam nose 90 that engages the washer 91 on the shoulder 92 of the valve stem 93. The valve stem is normally seated by the spring 94. The lower end of the valve stem operates in the sleeve 95 and then the chambered passageway 96. It terminates in a head 97 controlling the port 98. Fuel is admitted through the line 4, passageway 99, passageway 100, passageway 96 around and beneath the valve when the valve stem 93 and its head 97 are elevated.

30

35

30 *Operation*

When the engine is to be started by the usual 40 air starting system, the starting handle 53 is moved to the position indicated by A or the yoke 59 in Figure 5, which permits the rod 62, under the influence of the spring 65, to move the wedge 81 into maximum fuel injecting position so that, 45 as the engine is turned over by the air starter, electric starter, or any other means, the maximum of fuel under the predetermined pressure will be injected into the engine to facilitate starting. When the engine gets under way, the lever 50 53 is moved to position B of the starting yoke 59 in Figure 5. Thus, the amount of fuel to be injected is determined by the setting of the lever 53.

The adjustment of the position of the lever 26 55 will determine the compression of the spring 12 and thereby the point at which fuel oil will be by-passed and determine the maximum pressure of injection as the injection of the fuel takes place by the pressure thereon imparted by the 60 pump 2. Likewise, the setting of the lever 26 through the actuation of the shaft 23 determines the compression of the governor spring 35 and the speed of the engine is controlled. This speed of the engine controlled by the governor is reg- 65 ulated through the connection of the governor 38 having the studs 38a engaging through the yoke 38b mounted on the shaft 67 which in turn is connected to the yoke 66 with the governor rod 62, which it can operate within the limits set 70 by the yoke 59. Thus, the yoke 59 determines the maximum quantity of fuel which can be injected at the predetermined fuel pressure and the extent to which such injection takes place within the maximum so established depends upon 75

the action of the governor, which thus regulates the speed of the engine.

Consequently, there is an interdependence between:

5 (1) The determination of the maximum amount of fuel which can be injected for any given opening of the injector by the setting of the lever 53 and the positioning of the yoke 53.

(2) The control of the speed of the engine and 10 the amount of fuel injected within the maximum thus established by the governor operating the rod 62 and wedge 81 within the limits established.

(3) The sensitiveness or responsiveness of the governor within the range of its action is determined by the setting of the handle 26, shaft 23, 15 cup 34 and compression of the spring 35.

(4) The simultaneous adjustment of the fuel injection pressure by the adjustment of the compression of the spring 12.

20 It will be understood that the starter handle is at the same time the stop lever for the engine, permitting at any desired movement engine speed and fuel pressure to move the wedge out so as to discontinue the fuel injection, thus stopping the 25 engine.

It will be understood that I desire to comprehend within my invention such modifications as may be necessary to adapt it to varying conditions and uses.

30 Having thus fully described my invention, what I claim as new and desire to secure by Letters Patent, is:—

1. In combination, a source of fuel, means to deliver said fuel under pressure to an engine, adjustable means to by-pass at least a part of the fuel at a predetermined pressure, a governor for controlling the supply of fuel to the engine, yielding means for regulating the sensitiveness of the governor, and means for simultaneously adjusting 35 said yielding means and said adjustable means.

2. In combination, a source of fuel, means to deliver said fuel under pressure to an engine, adjustable means to by-pass at least a part of the fuel at a predetermined pressure, a governor for controlling the supply of fuel to the engine, and means for simultaneously adjusting the sensitiveness 45 of the governor and for adjusting said adjustable means.

50 3. In combination in an engine, a fuel injector, means having an adjustable pressure operated fuel by-pass, a governor operatively connected to the fuel injector means for controlling the supply of fuel to the engine, means for regulating the sensitiveness of the governor, and means to simultaneously regulate the regulating means of the 55 governor and the adjustable pressure operated fuel by-pass.

4. In combination, a source of supply of fuel, 60 means to deliver said fuel under pressure to an engine, a by-pass line from said means, means connecting said by-pass line with the source of supply, a valve in said means adapted to be opened by the pressure in the by-pass line to by-

pass part of the fluid under pressure, yielding means to maintain said valve closed, means for adjusting the compression of said yielding means, a centrifugally operated governor for controlling the supply of fuel to the engine, yielding means 5 for regulating the sensitiveness of said governor, and means for simultaneously adjusting both of said yielding means.

5. A fuel injection system for an internal combustion engine of the Diesel type comprising a 10 source of fuel supply under pressure, a fuel injection valve receiving fuel from said source of supply, engine driven means for operating said valve, an engine driven governor, means controlling the lift of the fuel injection valve regulated 15 by said governor, a by-pass line leading from said source of fuel supply, a by-pass valve in said by-pass line provided with a pressure regulating adjustment, the setting of which determines the fuel pressure in said source of fuel supply, means 20 for adjusting the sensitiveness of said governor and means for simultaneously regulating the pressure regulating adjustment of said by-pass valve and the means for adjusting the sensitiveness of said governor. 25

6. A fuel injection system for an internal combustion engine of the Diesel type comprising a source of fuel supply under pressure, a fuel injection valve receiving fuel from said source of supply, engine driven means for operating said valve, an engine driven governor, means controlling the lift of the fuel injection valve regulated by said governor, a by-pass line leading from said source of fuel supply, a by-pass valve in said by-pass line provided with a pressure regulating 35 adjustment, the setting of which determines the fuel pressure in said source of fuel supply, means for adjusting the sensitiveness of said governor, means for simultaneously regulating the pressure regulating adjustment of said by-pass valve 40 and the means for adjusting the sensitiveness of said governor and independent means for regulating the range within which said pressure regulating adjustment is adjusted.

7. In a fuel injection system for an internal 45 combustion engine, a source of fuel supply under pressure, a fuel injection valve receiving fuel from said source of fuel supply, engine driven means for periodically opening said fuel injection valve, adjustable means to regulate the maximum lift 50 of said fuel injection valve, an engine-driven governor, governor-controlled means for regulating the valve lift within said maximum, a by-pass line leading from said source of fuel supply, a by-pass valve in said by-pass line provided with 55 a pressure regulating adjustment, the setting of which determines the fuel pressure in said source of fuel supply, means for adjusting the sensitiveness of said governor and means for simultaneously regulating the pressure regulating adjustment 60 of said by-pass valve and the means for adjusting the sensitiveness of said governor.

GEORGE F. NOLTEIN.
